AUTOMATIC STARTING DEVICE AND SAFETY SHUT-OFF FOR GAS-FIRED INDUSTRIAL FURNACES

William J. Kerr, Waterbury, Conn., assignor to
The Bristol Company, Waterbury, Conn., a corporation of Connecticut

Application May 16, 1935, Serial No. 21,756

5 Claims. (Cl. 158—28)

This invention relates to electrically operated control mechanism for gas-fired industrial furnaces, and more particularly to automatic starting devices embodying safety shut-off means operative in case of extinguishment of the flame or electrical failure. The invention is concerned more especially with that type of control system in which the shut-off means is actuated by relay means governed in turn by a heat-sensitive element exposed to the influence of a flame in the heating system of such a furnace.

In industrial furnaces of the gas-fired type it is essential in the interests of safety that there be at no time an accumulation of unburned gases which may become ignited at one time and cause an explosion. To this end, it is necessary that gas be not admitted to the combustion chamber unless there be present an igniting agent, whereby complete combustion of the gas will be assured.

It is an object of this invention to provide means for automatically starting up a gas-fired industrial furnace, and at all times during the starting cycle preventing the accumulation of unburned gases.

A further object lies in the provision of means for interlocking the occurrence of the various events comprising the starting cycle, and introducing such time delays therein as may be expedient.

Still another object is to provide means whereby, in the event of interruption to the fuel supply or the extinguishment of the flame for any reason whatsoever, valves controlling the admission of fuel to the furnace will be closed and may not be reopened until the normal starting cycle is again initiated.

The invention has for an object, also, the provision of an electrically operated device of the above nature so embodied that, in event of failure of the essential circuits incorporated therein, or of the source of electrical energy for any such circuits, the system will revert to a condition in which no hazard exists.

The accompanying drawing is a diagrammatic representation of an industrial furnace having a starting and safety system in which one form of the invention is embodied.

As indicated in the drawing, 10 designates the combustion chamber of a furnace adapted to be heated by the combustion of gaseous fuel admitted through a burner 11, the flow of the fuel being controlled by a solenoid valve 12. Adjacent to the burner 11 is placed a smaller burner or pilot light 13, having incorporated therewith a spark plug 14, and receiving gas through a flow-

controlling solenoid valve 15. The spark plug 14 is connected to one terminal of the high-tension winding of an ignition transformer 16 having the other terminal grounded on the piping system. A thermocouple 17 is located within the furnace in close proximity to the pilot light 13, so that only when the gas from this burner is ignited will there be an appreciable electromotive force developed by the couple.

A control panel indicated at 18 carries the several relays and automatic devices (together with their electrical wiring and terminals) necessary to effect the interlocking and safety features hereinafter set forth.

Thus, a sensitive relay 20, of the type having an electrical winding 21 and contacts 22 adapted to be maintained in an open relationship by the influence of a unidirectional exciting current flowing in said winding, is actuated from the thermocouple 17. The said winding to this end is connected thereto through a series resistor 23 having an ohmic value selected to suit the critical temperature at which the relay is to become operative.

This relay is so adjusted that the maximum current which will flow in its electrical winding 21 under operating conditions will not be sufficient to open the contacts when they are in a closed position, but when mechanically moved to an open position by an externally applied force, said contacts will remain open so long as a maintaining current continues to flow. A relay suitable for this purpose is the Weston "Sensitrol" relay—model 705.

To move mechanically the said contacts, a cam member 25, having a contour 26 of uniform radius and a single depressed portion or indentation 27, is provided. The cam is to be driven at a constant speed by a motor 28, and serves to actuate two followers 29 and 30. The follower 29 takes the form of a lever member adapted to actuate mechanically the relay 20 in a sense to open its contacts 22 as the follower traverses the indentation 27 in the contour of the cam. The follower 30 is adapted to control the contacts 31 of a lever switch 32 in a sense that these contacts are caused to close when the follower rests upon the greater radius of the cam or contour 26 and to open as it passes over the indented portion 27.

In addition, the panel 18 carries three relays 35, 36 and 37, the relay 35 having a contact arrangement of the double-pole, single-throw, normally-open type and embodying the two sets of contacts 38 and 39. Relays 36 and 37 are both of the single-pole, double-throw type, the former

55

embodying the sets of contacts 40 and 41, and the latter the sets of contacts 42 and 43, with contacts 41 and 43 of the respective relays normally closed.

- 5 A manually actuated, normally open push-button switch 44 is placed in a position convenient for the operator of the furnace 10; and a source 45 of alternating current supply is made available to the system. The interconnections of the several devices on the panel 18 and their connections to the solenoid valves 12 and 15, the ignition transformer 16, the push-button switch 44 and the current supply 45, are as follows: Designating the conductors forming the two sides of the supply circuit by the numerals 50 and 51, the conductor 50 is connected to one terminal of the operating coil of each of the relays 35, 36 and 37, and also to one side of the low-tension winding of transformer 16 and to one side of the winding of motor 28. The operating coil of relay 37, the low-tension winding of transformer 16 and the winding of motor 28 are connected in parallel between conductor 50 and a common conductor 52 adapted to be brought into connection with the conductor 51 through the normally open contacts 39 of the relay 35. The operating coil of relay 35 is connected between conductor 50 and a conductor 53 from which a circuit may be completed to the conductor 51 through the switch 44 or the contacts 38 of the relay 35 in series with contacts 40 of relay 36 when the latter is energized. The operating circuit of relay 36 is completed between conductors 50 and 51 through the contacts 22 of relay 21. The actuating coil 47 of solenoid valve 15 is connected between the conductor 50 and a conductor 54, from which a circuit may be completed to conductor 51 through either the contacts 41 of relay 36 or contacts 42 of relay 37. The actuating coil 49 of solenoid valve 12 is connected between conductor 50 and a conductor 55, and the circuit completed therefrom to conductor 54 through the normally closed contacts 43 of relay 37. The contacts 31 of lever switch 32 serve to provide a connection between conductors 51 and 52 when the follower 30 is resting upon the portion of the periphery of cam 26 having the maximum radius.

Operation

- 50 The operation of the system is as follows: The various elements are shown in an inactive condition but with power applied, the cam 25 being located in its normal position of rest, and electrical power being applied to the terminals 46 of the system. The contacts 22 of relay 20 being closed, current will flow in the actuating coil of relay 36, causing its upper contacts 40 to remain closed and its lower contacts open. All other windings of the system will be "dead".

60 In order to start the furnace the operator presses the switch 44, energizing the relay 35 and causing both sets of its contacts 38 and 39 to be closed. The upper contacts 38, receiving current through the upper contacts 40 of relay 36, serve to lock the relay 35 in position, whereupon the push-button switch 44 is released, reverting to its normally open position.

65 Current through the lower contacts 39 of relay 35 will energize in parallel the motor 28, the relay 37 and the ignition transformer 16. The motor 28 will start, causing the cam 25 to rotate in the sense indicated by the arrow shown in the drawing. The actuating coil of relay 37 being energized, its lower contacts 43 will open and its upper contacts 42 will close, the latter serving to ener-

gize the solenoid 47 of the valve 15. This provides for the admission of fuel to the pilot burner 13, where, under normal conditions, it will be ignited by the spark plug 14.

70 The cam 25 having begun to rotate, the follower 30, which has been resting in the indentation, will rise to the portion 26 of greater radius, closing the contacts 31 of switch 32. This will serve to by-pass the lower contacts 39 of relay 35 and will maintain the conditions outlined above in 10 the event of the said relay 35 becoming de-energized. This action will continue without further change as the cam 25 performs the greater part of its revolution, or for a predetermined time, say 15 approximately one minute. During this time, if 15 conditions are normal in the furnace, the couple 17 will have become heated by the flame from the pilot light 13, and will be causing to circulate in the winding 21 of relay 20 a current tending to 20 actuate the relay, but not in itself of sufficient magnitude to cause the contacts 22 of this relay to be opened.

25 After the lapse of a time interval determined by the rotation of the cam 25, the follower 29 will enter the indentation 27 on the cam contour, and 25 will be caused to engage the relay 20 through a stem 48 thereof, mechanically actuating it in a sense to open its contacts 22. This will cause the relay 36 to be de-energized and released, opening its upper contacts 40 and closing its lower contacts 41.

30 The opening of the upper contacts serves to de-energize the locking circuit of relay 35, thereby releasing that relay, while the closing of the lower contacts of relay 36 serves to shunt the 35 upper contacts of relay 37. The release of relay 35 serves also to open both its sets of contacts, the upper set or locking contacts 38 having already been de-energized by the release of relay 36.

35 The opening of the lower contacts 39 of relay 35 transfers to the switch 32, still maintained in a closed position, such current as these contacts may have been carrying. After the lapse of a few seconds, the follower 29 rises from the 45 indented portion of the cam, disengaging the relay 20 and leaving it free to reset to its closed position.

40 If, during the cycle as thus far carried out, normal conditions have been established, the 50 thermocouple 17 will be causing to flow in the winding 21 of relay 20 sufficient current to maintain the contacts in their open position after having been disengaged by the cam follower 29. Furthermore, as soon as the follower 29 has disengaged the relay 20, the follower 30 will enter the indentation 27 in the contour of the cam, opening the contacts 31 of switch 32, and thereby de-energizing the ignition transformer 16, the relay 37 and the driving motor 28, thus bringing 60 the cam to rest.

45 Assuming the relay 20 to have been maintained in its open-circuit position as above set forth, the release of relay 37 will open its upper contacts 42 (already bridged by the lower contacts 41 of relay 36) and will close its lower contacts 43, thereby energizing the solenoid 49 of the main fuel valve 12. This causes gas to be admitted to the main burner 11, where it will be ignited by the flame from the pilot burner 13, thus 70 establishing a normal condition of operation, with both the main and pilot burners operating, the ignition transformer 16 de-energized, and the cam 25 in its normal position of rest.

50 In the event of the gas failing to ignite during 75

the preliminary part of the cycle, or of the thermocouple or its circuit proving defective, there will be no current flowing in the winding of the relay 20 at the time of the release of its contacts 5 22 through the action of the follower 29, so that its said contacts will re-close, re-energizing relay 36, whose lower contacts 41, being thus opened, no longer serve to shunt the upper contacts 42 of relay 37. Thus, as the cam continues 10 its rotation, and the switch 32 is opened, releasing relay 37, there will remain no alternative circuit for the current to the solenoid valves, so that the pilot burner will at once be shut off and the valve 12 to the main burner will not be opened. 15 The ignition transformer will then be de-energized and the motor 28 will come to rest in the normal manner.

In the event of a fault developing in the thermocouple circuit during operation, the relay 20 20 will immediately be de-energized and released, energizing relay 36 and closing both fuel valves as hereinbefore set forth. If an intermittent contact should develop in the thermocouple circuit, the first interruption of the current will release the relay 20, and as a return of current will 25 not alone be able to actuate the relay to reopen its contacts, the fuel will remain shut off until there is initiated a normal starting cycle, including a complete rotation of cam 25.

30 In the event of an interruption to the fuel supply to the pilot, the cooling of the thermocouple will again cause the relay 20 to be released, closing the fuel valves, which will not be reopened until the normal starting cycle is carried out. Should an interruption to the electrical supply occur, the fuel valves will automatically close and remain closed so long as the power supply is interrupted. If power should be restored before the couple 17 has cooled sufficiently to release relay 20, the valves will be reopened; and if flame be present in the furnace, the burners will be re-ignited and normal operation resumed. If, on the other hand, the burners are not re-ignited, the couple will quickly 40 reach a temperature at which the relay 20 will be released before there can accumulate sufficient fuel to introduce a hazardous condition, thus closing the fuel valves, which then cannot be reopened without carrying through the normal 45 starting cycle.

50 Thus, there have been provided automatic means whereby the furnace must be carried through a definite starting cycle in order to establish normal operation, and in the event of the occurrence of any one of a group of events likely to introduce operating hazards, the system reverts to a condition of safety.

While throughout the specification and claims the term "gas-fired" has been utilized in connection with the furnace, it is to be understood that the furnace may be fired with a liquid fuel such as oil and control effected thereof as set forth without requiring any change other than, of course, in the nature of the burner means.

65 I claim:

1. The combination with a fluid fuel burner, an electrical igniter for the same, and electrical means controlling the supply of fuel to said burner; of a control system comprising in circuit a main switch, said igniter, said fuel-supply-controlling means, a motor-operated sequential switching mechanism, and a plurality of inter-dependent relays, whereby in response to closure of said main switch, energization of one of said 70 relays effects operation of said igniter, the fuel-

supply-controlling means and the motor-operated sequential switching mechanism; a mechanically controlled relay subsequently and momentarily mechanically actuated from the motor of the sequential switching mechanism; a switch 5 forming a part of said switching mechanism to de-energize said motor, said one relay and the igniter; and a temperature-sensitive element responsive to the burner and operative to maintain said mechanically actuated relay in its 10 actuated position, whereby upon release of said one relay with said mechanically actuated relay remaining energized, said fuel-supply-controlling means continues to supply fuel to said burner. 15

2. The combination with a fluid fuel burner, an electrical igniter for the same, and electrical means controlling the supply of fuel to said burner; of a control system comprising in circuit a main switch, said igniter, said fuel-supply-controlling means, a motor-operated sequential switching mechanism, and a plurality of inter-dependent relays, whereby in response to closure of said main switch, energization of one of said 20 relays effects operation of said igniter, the fuel-supply-controlling means and the motor-operated sequential switching mechanism; a mechanically controlled relay subsequently and momentarily mechanically actuated from the motor of the sequential switching mechanism; a 25 switch forming a part of said switching mechanism to de-energize said motor, said one relay and the igniter; and a temperature-sensitive element responsive to the burner and operative to maintain said mechanically actuated relay in 30 its actuated position, whereby upon release of said one relay with said mechanically actuated relay remaining energized, said fuel-supply-controlling means continues to supply fuel to said burner and upon release of said one relay with said mechanically actuated relay not 35 electrically energized by the temperature-sensitive element, said fuel-supply-controlling means ceases to supply fuel to said burner. 40

3. In a control for a fluid fuel furnace having a main burner and a pilot light: a temperature-sensitive element thermally associated with said pilot light, shut-off means for said main burner, means associated with said shut-off means for actuating the same to an open position and including an electromagnetic element having a winding permanently in circuit with said temperature-sensitive element and tending under the influence of current therefrom to maintain said electromagnetic element in a position to permit actuation of said shut-off means to an open position, said winding being so proportioned that current therein representing normal operating temperature at said pilot light is sufficient to maintain said electromagnetic element in said 45 permissible position but insufficient to give it motion to said position, together with motor-driven timing means establishing a definite time cycle and exerting a transient influence for mechanically effecting said motion and subsequently terminating said influence, and for causing said shut-off means to be moved to an open position upon maintenance of said electromagnetic element in said permissible position after the 50 termination of said transient influence. 55

4. In a control for a fluid fuel furnace having a main burner and a pilot light and separate electrically operated means for governing the supply of fuel to each: a temperature-sensitive electrical element thermally associated with the 75

pilot light, a relay provided with contacts to effect the operation of said means and having a maintaining winding in circuit with said element, manually operable additional contacts for energizing said pilot-light means, a motor-operated timing mechanism for mechanically positioning said relay in a position to be maintained by the influence of current in said maintaining winding and for opening said main-burner means if said relay is so maintained, and for de-energizing said pilot light fuel-supply-governing means if said relay is not so maintained.

5. In combination with a fluid fuel burner, a pilot burner, an electrical igniter for the same, 15 and electrical means controlling the admission of fuel to each of said burners; a temperature-sensitive element responsive to the flame of the pilot burner; a control system comprising a main switch, said igniter, said fuel-controlling 20 means, a motor-operated sequential switching mechanism, a plurality of interdependent relays

so arranged and connected in circuit that in response to closure of said main switch, energization of one of said relays effects operation of said igniter, the fuel-controlling means for the pilot burner and the motor for the sequential switching mechanism to subsequently and momentarily mechanically actuate another of said relays and the switch of said switching mechanism, which latter serves to de-energize said motor, said one relay and the igniter, and the 10 said other relay being in circuit with said temperature-sensitive element and adapted to be maintained thereby in its actuated position; and a further one of said relays controlling the supply of fuel to the main burner and, upon release of said one relay with said mechanically actuated relay maintained in its actuated position, serving to establish and maintain the supply of fuel to said main burner.

WILLIAM J. KERR.
